UNITED STATES PATENT OFFICE.

GIUSEPPE RUBELLO, OF MILAN, ITALY.

MACHINE FOR THE MANUFACTURE OF CARDBOARD BOXES.

Application filed August 1, 1922. Serial No. 578,934.

To all whom it may concern:

Be it known that I, GIUSEPPE RUBELLO, subject of the King of Italy, residing at Via Gustavo Modeno 6, Milan, Italy, have 5 invented certain new and useful Improvements in Machines for the Manufacture of Cardboard Boxes, of which the following is a specification.

The present invention relates to machines 10 for making boxes from cardboard tubes.

The essential object or purpose of the machine according to this invention is to produce small rings of cardboard with a common rounded edge or with a projecting edge 15 on one of the ends of the rings themselves and of the dimensions desired by the operator. The said small rings with the common successive application of the small base inserted therein and the gummed label, form 20 the box well known in commerce and used in particular in pharmacy, perfumery and for other specialties. Whereas by the system now in use the small ring, cut out previously of suitable dimensions by means of 25 the apparatus already in existence, is placed with the bottom beneath the die so as to be provided thereby at the first stroke thereof with the flange and then by a second stroke thereof with the gummed label, the machine 30 now about to be described is adapted to produce the small ring already flanged, thereby economizing time to a considerable extent in the manufacture of the small box.

Another very important feature of this invention is the production, at the same time and by the same means, of small projecting flanged rings, for the production of which special and complicated dies are otherwise necessary. A further advantage is the price 35 of the dies to be used in the press which are more simple and less costly.

In the accompanying drawings showing a construction of the machine according to this invention by way of example—

40 Figure 1 is a perspective view.

Figure 2 is a side view of the small hand wheel and of part of the flanging apparatus or cylinder.

Figure 3 shows, partially in section, the 50 details of the cone cylinder, and

Figure 4 is a section thereof on the line A—B of Figure 3.

55 Figures 5 and 6 are a section and a front view respectively of the flanging apparatus or cylinder for the production of the small

rings of cardboard with the common rounded flange as shown in Figure 7.

Figure 7 is a side view of the cardboard ring as produced by the apparatus shown at Figures 5 and 6.

60 Figures 8 and 9 are respectively a front view of the said flanging apparatus or cylinder modified for the production of small rings of cardboard with a projecting flange as shown in Figure 10.

65 Figure 10 is a side view of the flanged cardboard ring.

As shown in the drawings, the machine 70 is composed of the table of iron or cast iron 1, in which are bored the holes necessary for fixing the different parts and a larger hole 2 through which the work already cut out, falls into a basket.

75 In the lower part of the table 1 carried on its two standards 3 and 4, is mounted a suitable cross bar which carries two pedals one of which serves to operate the apparatus 5 for cutting out the cardboard tube, while the other serves to raise, by means of levers 6 and 7, the flanging apparatus 8 so that the 80 workman can slip the cardboard tube on to the shaft 9, pushing it just up against the grooved cone 10 of movable headstock 11. The external grooving of the said cone 10 affords sufficient grip on the cardboard tube 85 to enable it to be pushed while rotating towards the flanging apparatus 8 and subsequently to be returned.

The shaft 9 is carried on the bracket 12 in ball bearings between which are mounted 90 two pulleys 13 and 14 the first one of which (13) is a loose pulley and the second one (14) a fast pulley which transmits movement to the machine.

The shaft 9 carries on the one hand on one 95 of its ends the grinder 15 for sharpening, when needed, the tools for cutting out the work, while the other end of the shaft 9 projecting from the bearings is extended outwards for a length of about forty five centimetres and terminates in a screw 16 (see Figure 3) which serves to carry the cone cylinder 17. In this extension of the said shaft 9 and along its whole length is cut the groove 18 in which slide the two projections 19 and 20 of the internal bearing of the movable headstock 11 with the grooved cone 10 for carrying the tube.

The said movable headstock 11 with the grooved cone for carrying the tube carries, 110

by a simultaneous to and fro and rotary movement, the tube in such a way as to enable the flange to be produced and cut successively without interruption. The said 5 headstock is constituted by the post 21 which is adapted to move by sliding in the slot 22, to the right or left at will by means of a hand wheel 23 and the gear wheel shaft 24, as indicated by the arrows in the drawing, 10 for the purpose of enabling the flange to be produced on the tube already cut out and then brought back to its original position.

The said movable headstock 11 contains in its interior, as shown in Figure 3, the 15 bearing 25, provided on its exterior with the groove 26 in which the screw 27 slides. This latter by sliding in the said groove 26, is for the purpose of enabling the revolving bearing 25 on the shaft 9 to be 20 brought or moved to the right or left while both bearing and shaft rotate together.

This bearing 25 also carries in its interior, the two projections 19 and 20 referred to, which slide with a to and fro 25 movement in the groove 18 in the shaft 9, which groove while it acts as a guide for the said to and fro movement acts also as a retaining point for the projections 19 and 20 so that the rotary movement of the shaft 30 9 may be transmitted to the bearing 25 carrying with it the grooved cone 10 and the cardboard tube.

The bearing 25 terminates, at one of its ends in a collar, and on the other end, which 35 is screw-threaded, is screwed on the cone 10, the circumference of which is variable according to the diameter of the cardboard tube to be cut out and has its exterior grooved so as to grip the tube internally 40 and thus render possible the movements of the tube required for its manufacture.

The cone cylinder 17 and also the grooved cone 10 carrying the tube, varies always according to the diameter of the tube to be 45 cut out, and its cylindrical part is naturally of a diameter which is equal to the internal diameter of the tube itself. That it should act at the same time as a support is very important as it is on this cylinder 50 that the flange is formed and this cylinder keeps the tube equidistant from the centre of rotation. As shown in the drawing, the cone cylinder 17 terminates, on the conical side, in the cylindrical piece 28 of smaller 55 diameter, which is introduced when the flange is being formed, into the corresponding tubular cavity 29 or 29^a of the flanging apparatus or cylinder 8 or 8^a. This cylindrical piece 28 acts as a stop for the edge 60 of the cardboard tube when it bends by preventing it from continuing to wind. By the action of the said stop all the small rings of cardboard which it is desired to cut are produced of the same size. In the cone 65 cylinder 17 is bored a hole 30 for the escape

of air. The cutting out apparatus 5 is fixed to the table 1 exactly beneath the cone 17.

By means of three ovals cut in the part where the said apparatus is fixed, it can be moved to the right or left to the extent 70 of several centimetres according to the height of the small ring of cardboard which it is desired to cut out. This height can also be obtained by means of the cone cylinder 17 by screwing it more or less on to the 75 shaft 9.

Naturally by being able to vary the diameter of the cone 17 according to the diameter of the cardboard tube to be cut out the cutting tool can also be raised or 80 lowered relatively thereto.

The flanging apparatus 8 is mounted on the shaft 31, the screw-threaded end of which acts as the centre does in an ordinary lathe, and carries on its opposite end, the gear wheel 32 which receives movement through the gear wheel 33 from the small hand wheel 34, by means of which the flanging apparatus can be moved forwards or backwards, with rapidity according to requirements. This shaft 31 is carried by the two levers 35 and 36 bearing on the shaft 37 which is carried in the small support which is fixed to the table 1. The flanging apparatus or cylinder 8, which serves to produce the small rings with the common rounded edge (see Figures 5, 6 and 7), is hollow and its diameter can be varied according to the diameter of the cardboard tube to be 90 flanged and has in its interior, on a flat part of the said tubular cavity 29 the teeth 39 which bend over and flange the cardboard tube when this latter in its rotary movement is thrust against said teeth. Against the bottom of the tubular cavity 29 bears 95 the external surface of the cylindrical piece 28. In the flanging apparatus or cylinder 8^a (see Figures 8, 9, 10) which produces the small rings with the projecting edge, the teeth 39^a are of greater width than that 100 of the cardboard tube to be flanged (the said teeth 39^a being also adapted to form the edge 40) so that the tube during its manufacture, not being able to bend towards the lower part owing to the obstruction offered by the cylindrical part 28, is 105 compelled by the pressure of the advance to extend over the said flange 40, for the whole width of this latter, and, in any case 110 to bend towards the outer part so as to 115 form the above mentioned projecting edge 41 of the small cardboard ring (see Figure 10).

The said levers 35 and 36, which, as has already been stated above, are pivoted on the shaft 37 and rotate with it to an extent which is sufficient to enable them to be raised so as to allow the cardboard tube to be slipped on to the shaft 9 are afterwards arrested in their rearward or descending 120 125 130

movement and resume their normal position relatively to the cone cylinder 17, by the screws 42 fixed on the extension of the small support 38. These screws also serve to adjust the flanging apparatus upwards and downwards so that it can be arranged exactly opposite or at the same level as the tube so as to enable the flange to be produced with accuracy. On the lever 7 are mounted the two spiral springs 43, 44, for the purpose of thrusting the lever 7 downwards.

The operator, seated in front of the machine, commences by depressing the pedal 15 so that by raising the flanging apparatus, he can slip the cardboard tube on and thrust it against the grooved cone 10. The cylinder 17, the diameter of which is equal to the diameter of the interior of tube, allows the 20 operator to place the said tube in a suitable position and equidistant from the centre of rotation, as already explained. The operator then sets the machine in motion, and, by means of the hand wheel 34, the gear wheels 25 32 and 33 and the movable headstock 11, he can thrust the cardboard tube to be flanged, which he has already lowered, as soon as he has slipped it on, and after having thrust it against the cone cylinder, he forms the 30 flange thereon. Afterwards, after having withdrawn the flanging cylinder, by depressing the other pedal the operator lifts the cutting tool 5 and cuts the small ring of cardboard to the dimensions desired and by 35 the same tube pushes it off the cylinder and causes it to fall through the hole 2. The movement takes place in an exactly similar manner until the cardboard tube is finished and a new one put in its place, when the 40 operation is repeated and so on.

Besides the system above described for producing the movement and the rotation of the movable headstock 11, this movement may also be obtained by reversing the parts, that is to say, by providing a projection or 45 cam over the whole length of the part of the shaft 9 which projects and by forming a corresponding slot in the internal part of the bearing 25 of the movable headstock 11.

50 This cam on the shaft by entering the said

slot transmits its movement of rotation and at the same time acts as a guide for the movement of the tube to the right or left as already explained.

What I claim and desire to procure by 55 Letters Patent of the United States, is:—

1. A machine for the manufacture of cardboard boxes from tubes, comprising a supporting table, a bracket mounted on the table, a shaft carried by the bracket, a movable headstock on the table, a grooved cone—carried on said headstock—for gripping and carrying the tube, a cone cylinder located on the end of the said shaft, flanging means mounted on the table, and means also 60 65 mounted on the table for cutting off each box.

2. In a machine for the manufacture of cardboard boxes from tubes, according to claim 1, the movable headstock having the 70 cone grooved to carry the tube, and the cone having at the same time a to-and-fro and a rotary movement for the purpose of producing the flanging of the cardboard tube which 75 rotates with it.

3. In a machine for the manufacture of cardboard boxes from tubes, according to claim 1, the cone cylinder, acting as a support for effecting the cutting of the tube itself and also for keeping the tube equidistant from the centre of rotation of the shaft itself, and a conical end formed on said cone cylinder and terminating in a smaller cylindrical portion constituting a stop for the flange and also producing thereon the 80 85 projecting edge.

4. In a machine for the manufacture of cardboard boxes from tubes, comprising a supporting table, a rotating shaft mounted on the table, a cone cylinder on the shaft, 90 flanging apparatus, mounted on the table and having a tubular cavity into which the cone cylinder is introduced when the flange is being formed, and means whereby the flanging apparatus itself can be raised in 95 order to allow of the setting of the tube on to the said rotating shaft.

In testimony whereof I affix my signature.

GIUSEPPE RUBELLO.
